[57] CLAIM

The ornamental design for an external modem enclosure for a data processing system, as shown and described.

DESCRIPTION

FIG. 1 is a top, front, right side isometric view of an external modem enclosure for a data processing system, showing our new design;

FIG. 2 is a front elevational view thereof;

FIG. 3 is a right side elevational view thereof, the left side being identical;

FIG. 4 is a top plan view thereof;

FIG. 5 is a bottom plan view thereof;

FIG. 6 is a rear elevational view thereof;

FIG. 7 is a top, front, right side isometric view of an external modem enclosure for a data processing system, showing a second embodiment of our new design;

FIG. 8 is a front elevational view thereof;

FIG. 9 is a right side elevational view thereof, the left side being identical;

FIG. 10 is a top plan view thereof;

FIG. 11 is a bottom plan view thereof;

FIG. 12 is a rear elevational view thereof;

FIG. 13 is a top, front, right side isometric view of an external modem enclosure for a data processing system, showing a third embodiment our new design;

FIG. 14 is a front elevational view thereof;

FIG. 15 is a right side elevational view thereof, the left side being identical;

FIG. 16 is a top plan view thereof;

FIG. 17 is a bottom plan view thereof; and,

FIG. 18 is a rear elevational view thereof.

The three embodiments are identical in all respects except for the left portion of the front panel and the electrical connections on the rear panel.
